ADJUSTABLE AREA RESTRICTING MEMBERS FOR SUCTION NOZZLES

Emil Anderson, Ossining, N.Y., assignor to Electrolux Corporation, Old Greenwich, Conn., a corporation of Delaware

Application June 30, 1955, Serial No. 519,187

6 Claims. (Cl. 15—354)

My invention relates to vacuum cleaner nozzles and more particularly to a nozzle intended for cleaning soft floor coverings.

Certain of the more recent rug constructions, particularly those involving loops made of relatively large diameter cords, are difficult to clean by means of an ordinary suction nozzle because these loops extend into the nozzle opening and engage the edges of the lips, thus offering high resistance to movement of the nozzle. To overcome this it has been proposed to provide means within the nozzle opening having a gliding surface for supporting the nozzle on the rug and at the same time preventing the entrance of the cords or tufts of the rug into the nozzle opening. However, I have determined that different rug constructions require different spacings of these gliding surfaces from the plane of the lips of the nozzle, and it is a principal object of the present invention to provide an arrangement whereby these gliding surfaces may be adjusted with respect to the nozzle lips.

Further objects and advantages of my invention will be apparent from the following description when considered in connection with the accompanying drawings, which form a part of the specification and of which:

Fig. 1 is a bottom view of one embodiment of my invention;

Fig. 2 is a rear view chiefly in cross-section taken on the line 2—2 of Fig. 1;

Fig. 3 is a bottom view of a second embodiment of my invention;

Fig. 4 is a rear view chiefly in cross-section taken on the line 4—4 of Fig. 3;

Fig. 5 is a rear view chiefly in elevation, showing certain parts in different positions from that shown in Fig. 4; and

Fig. 6 is a cross-sectional view taken on the line 6—6 of Fig. 4.

Referring more particularly to Figs. 1 and 2, reference character 10 designates generally a suction nozzle including a hollow body member 12 formed with an elongated suction opening 14. An elbow 16 is rotatably secured to the rear of the body 12 and communicates with the interior thereof and consequently with suction opening 14. The usual suction conduit may be connected to the outer end 18 of elbow 16.

A stamping 20 is secured within body 12 and has a lip portion 22 which constitutes the forward lip of the nozzle, the central part of which may be formed with serrations 23. The rear lip may comprise a rod 24. Both stamping 20 and rod 24 are secured in place by being clamped underneath stampings 26 which are secured to opposite ends of the nozzle by means of bolts 28. These stampings 26 are formed with gliding surfaces 30. Stampings 26 also serve to retain a bumper ring 32 of rubber or other suitable material.

Referring to Fig. 2, it will be seen that on either side of the center of the nozzle two rods 36 and 38 extend transversely of the nozzle opening 14. Each rod 38 extends through a slot 40 in a gliding member 42 which is

2

formed with a gliding surface 44 disposed substantially parallel to the plane of the opening 14 as defined by the lips 22 and 24. Each member 42 is formed with an inclined surface which is substantially parallel to elongated slot 40 and in which is formed a pair of grooves 46 and 48, within one or the other of which is received the pin 36. A spring 50 is secured to each member 42 by means of a bolt 52 and overlies the grooves 46 and 48. As is shown more clearly in Fig. 1, members 42 are formed with relieved portions 54 on either side thereof so as to provide air channels between the members 42 and the lips 22 and 24. Also, an air channel is provided between the members 42 and the nozzle body, as is shown at 56 in Fig. 2, so that air may flow from the ends of the elongated opening 14 to the elbow 16.

As will be seen in Fig. 2, the member 42 located to the left of the center of the nozzle has its gliding surface 44 substantially flush with the plane of the nozzle lips. In this position, the rod 38 is in the outer end of the inclined slot 42, while the rod 36 occupies the groove 48. The member 42 at the other end of the nozzle, on the other hand, is shown in a position in which its gliding surface 44 projects outwardly beyond the plane of the nozzle lips. In this position the rod 38 occupies the inner end of the slot 40, while the rod 36 occupies the groove 46.

In order to shift the member 42 from the position shown at the left of the drawing to that illustrated at the right, the thumb is placed on the right-hand end of the member and pressed downwardly to the left, in the direction indicated generally by the arrow 58. This force causes the member 42 to pivot in a clockwise direction about the rod 38, the rod 36 moving out of the groove 48 against the resistance of spring 50. The horizontal component of the force represented by the arrow 58 moves the member 42 to the left until rod 38 occupies the inner end of slot 40 and the rod 36 occupies groove 46. In order to move the member 42 from the position shown at the right of the drawing to that illustrated at the left, a finger may be placed underneath the outer end of the member to apply a force upwardly and towards the left as indicated by the arrow 60. This causes the member 42 to pivot counterclockwise about the rod 38 so as to bring the rod 36 out of the groove 46. At the same time the left-hand component of the force slides the member 42 to the left causing the rod 38 to occupy the outer end of the slot 40 and the rod 36 to occupy the groove 48. During this movement the spring 50 is flexed sufficiently to permit the member 42 to pass by the rod 36. Normally, the spring retains the member in position with the rod 36 in one or the other of the grooves.

While for purposes of illustration, the respective members 42 have been shown in different positions, ordinarily both of these members will be in the same position, that is both either will have their gliding surfaces 44 flush with the plane of the nozzle lips, or both will have their gliding surfaces projecting outwardly, and the operator is able to select the position which is best suited for the type of rug being cleaned.

In the embodiment illustrated in Figs. 3 through 6 the gliding members are readily removable from the nozzle, as well as being adjustable therein. As is shown more clearly in Figs. 4 and 5, stampings 26 are provided with inwardly extending projections 62 under which may be engaged the outer ends of a pair of spring arms 64. The inner ends of these arms are secured together by means of a pair of arcuate members 66, which bridge the inner end of rotatable elbow 16. The removable insert consisting of the arms 64 and connecting pieces 66 are shown in Fig. 5 in an intermediate position during removal or insertion into the nozzle. Assuming that the piece is being inserted, the application of force for example to the arcuate members will cause the spring arms 64 to be so

deflected that the piece will snap into the position shown in Fig. 4, where the resiliency of the arms holds it in place against the inner walls 68 of the stamping 20. As will be seen these walls are inclined with respect to the plane of the suction opening and consequently, when inserted, the spring arms 64 are likewise so inclined.

Slidably mounted on each spring arm 64 is a gliding member 70. These gliding members have the hollow construction shown in Fig. 6 and the spring arms 64 extend therethrough. When the insert is in place, the inner walls 72 of the members 70 are disposed between the spring arms 64 and the inclined walls 68 and movement of each member 70 is resisted by friction. It will be seen that if the members 70 are slid along the spring arms 64 they will be caused to project more or less through the nozzle opening. In the full line positions shown in Fig. 4, where the members 70 are both moved towards the center of the nozzle, their gliding surfaces 74 are retracted slightly inwardly beyond the plane of the nozzle opening, while in the dotted line positions in which the members 70 have been slid to the ends of the nozzle, their outer surfaces project somewhat beyond the plane. Each member 70 may be retained in either of these positions by means of a pair of recesses 80 formed in each spring arm 64 which cooperates with a projection 82 formed on the rear wall 72 of each member 70. The members 70 may be shifted between these two positions by applying force thereto by means of the finger in the proper direction to cause them to slide along the spring arms 64.

It will be noted that the hollow construction of members 70 permits the passage of air therethrough so that air may pass from the ends of the nozzle opening to the centrally located elbow 16.

It will be further noted that when the gliding members of each of the disclosed embodiments are adjusted outwardly of the plane of the nozzles, the volumetric displacement of the gliding member structure within the suction opening of the nozzle will be reduced and thus the velocity characteristics of the inflowing air to the outlet will be changed. Thus, by longitudinally adjusting the gliding members the configuration of the suction opening may be controlled, this being especially desirable when encountering different surfaces to be cleaned including rugs or carpets having different pile lengths.

While I have shown and described two more or less specific embodiments of my invention it will be understood that this has been done for the purpose of illustration only and that the scope of my invention is not to be limited thereby, but is to be determined from the appended claims.

What I claim is:

1. In a vacuum cleaner nozzle, a hollow elongated body including co-planar lips bounding an elongated opening, an outlet conduit communicating with the central part of said hollow body, the inner wall of said body opposite said opening having oppositely inclined portions so as to be closer to the plane of said opening adjacent to the ends of said body than adjacent to the center thereof, a pair of gliding elements disposed in said opening one on each side of said conduit for contacting a surface being cleaned, and means for slidably supporting said elements with respect to said inclined portions so that displacement of said elements along said inclined portions changes the distance between said elements and the plane of said opening, said elements being hollow so as to provide passages for flow of air from the ends of said suction opening through said elements to said outlet conduit.

2. In a vacuum cleaner nozzle, a hollow elongated body including co-planar lips bounding an elongated opening, an outlet conduit communicating with the cen-

tral part of said hollow body, the inner wall of said body opposite said opening having oppositely inclined portions so as to be closer to the plane of said opening adjacent to the ends of said body than adjacent to the center thereof, elongated structure resiliently engageable within said body through said opening, said structure being resiliently pressed against said inclined portions, a pair of hollow wedge-shaped gliding elements disposed in said opening one on each side of said conduit and having an outer face for contacting a surface being cleaned, said structure extending through said elements and urging an inner face of each element against one of said inclined portions, said elements being displaceable along said structure and said inclined portions so as to change the distance between said outer faces and the plane of said opening.

3. A suction nozzle for cleaning a surface comprising an elongated hollow body having a pair of spaced elongated walls, the lower edges of said walls forming lips bounding a suction opening of substantially uniform width, means for connecting a source of suction to said hollow body near the longitudinal center of said opening, a surface contacting member in each end of said body, said members being spaced from each other and each member extending from adjacent one end of said opening to adjacent said means and having a lower surface disposed near the plane of said opening, said members being spaced inwardly substantially equal distances from said walls, said surface contacting members being formed with longitudinal portions inclined respectively relative to the plane of said opening and in converging relation with each other, means providing portions fixed with regard to said body and cooperating with the inclined portions of said members, said members being displaceable toward and away from each other longitudinally within said elongated opening and longitudinally relative to said fixed portion to adjust the surfaces parallel to the plane of said opening and for controlling the configuration of the suction opening, and means retaining said members in the positions to which they are longitudinally displaceable.

4. The structure of claim 3 in which said longitudinal portions on said members comprise slots extending transversely through said members, and means providing portions fixed with respect to said body comprising pins extending through said slots and transversely of said body below the lips of said section opening.

5. The structure of claim 3 in which said longitudinal portions of said members comprise an edge portion on said members diverging longitudinally from the ends of said members farthest from said central portion and extending toward the central portion, and said means providing portions fixed with respect to said body comprise inclined surfaces on said body diverging longitudinally from the end thereof farthest from said central portion and extending toward the central portion, said surfaces on said members being complementary to the inclined edge portion of the members which they engage.

6. The structure of claim 3 including resilient means interposed between said members and said body aiding to retain said elements in a position of adjustment relative to said suction opening.
